TYPEWRITING MACHINE

John Joseph Kittel, St. Albans, N. Y., assignor to
Royal Typewriter Company, Inc., New York,
N. Y., a corporation of New York

Original application April 25, 1938, Serial No.
204,235. Divided and this application October
19, 1939, Serial No. 300,278.

6 Claims. (Cl. 197—151)

This application is a division of my co-pending application Serial No. 204,235 for improvements in Typewriting machines, filed April 25, 1938.

The invention relates to typewriting machines, and more particularly to ribbon feeding mechanism for typewriting machines. Mechanism embodying the present invention is, however, especially adapted for the feeding of ribbons or strips of "hectograph" or other kinds of transfer medium in the use of which it is desirable to present a complete new or unused portion of the transfer medium, at the printing line, for each new character typed in a line of typing.

An object of the invention is to provide a ribbon feeding mechanism operable in response to actuation of a line-spacing lever in a manner to feed a strip of fresh unused ribbon along the printing line of the platen corresponding substantially in length to the length of an average typed line.

Other objects will become apparent from a reading of the following description, the appended claims, and the accompanying drawings, in which:

Figure 1 is a top plan view of a typewriting machine with some parts omitted and showing mechanism embodying my invention applied thereto;

Figure 2 is a fragmentary top plan view of ribbon feeding mechanism shown at the left-hand end of the typewriter carriage in Figure 1, and drawn on an enlarged scale;

Figure 3 is a view in side or end elevation as viewed when looking in the direction of the arrow 3 in Figure 1, and drawn on an enlarged scale;

Figure 4 is a sectional view taken on the line 4—4 of Figure 2;

Figure 5 is an inverted section taken on the line 5—5 of Figure 4 and drawn on a reduced scale with respect to Figure 4; and

Figure 6 is a fragmentary end elevation looking in the direction of the arrow 6 in Figure 1.

The drawings show one embodiment of the invention as applied to a Royal standard typewriting machine, but it is to be understood that mechanism embodying the invention may be applied to other typewriting machines.

The machine shown in the drawings includes a stationary main frame A and a carriage generally designated B mounted on the main frame for reciprocatory movements in the usual manner, viz., an intermittent or step-by-step movement from right to left which is effected by a motor and an escapement mechanism actuated

by the key levers or the space bar, and a return movement from left to right. Such an escapement mechanism is shown, for example, in the Patent Number 1,212,939, issued January 16, 1917, to George F. Handley.

The carriage includes the usual end plates 1 and 2 in which is journaled a platen 3; and also mounted on the carriage are the usual paper apron and bottom feed rollers (not shown) for feeding a master sheet C forwardly and thence upwardly in front of the platen. Mounted on the carriage is a bail 4 including a rear cross bar 5, and spaced supporting arms 6—6 connected at their forward ends by a bar 7 having journaled thereon pressure rollers 8—8 for directing usual work sheets (when such are used) rearwardly over the platen after they have passed above the printing line. The arms 6—6 extend from the cross bar 7 rearwardly over the platen and are pivotally connected as at 9—9 to the upper ends of arms 10—10 which, in turn, are pivotally mounted as at 11 on the carriage end plates 1, 2 (see Figure 3). Springs 12 interposed between the arms 6 and the carriage end plates urge the arms downwardly so as yieldably to hold the pressure rollers 8 against usual work sheets, and the latter against the platen. Formed integrally with the end plate 1 is a laterally extending shelf 13 on which a combined line spacing and carriage return lever 14 is pivotally mounted as at 15 and is connected to the platen 3 in the usual manner by means of a link 16 connected to a rock arm 17, the latter carrying a pawl 18 engageable with a ratchet wheel 19 on the platen (see Figure 2). The lever 14 includes the usual handle portion which extends forwardly so as to be positioned within easy reach of the operator. Ribbon spools 20—20 are shown mounted on the main frame in the usual manner, a reversible inking ribbon 21 being adapted to be unwound from one of the spools 20 and wound upon the other, as is customary.

The typewriting machine as thus far described is not claimed per se as constituting the present invention, it being understood that the invention comprises parts to be hereinafter described and combinations of such parts with each other and with the known typewriting machine construction already described.

Although the invention is not necessarily restricted to the use of ribbon feed mechanism adapted to be mounted on or applied to typewriting machines of standard or known construction, it is desirable in many cases to apply the feed mechanism to such machines, and for

the purposes of illustration the drawings show an embodiment which may be fitted compactly to a machine of known construction without substantially increasing the over-all size of the machine and without its being necessary to alter the machine structure in any material respect.

In the form shown, a roll ribbon supply generally designated D is mounted at the right hand end of the carriage, and the "hectograph" or other transfer medium ribbon 22 is arranged to be fed from the roll along the printing line of the platen in a manner to be described. In order to protect the master sheet and to prevent it from being marred by the ribbon 22, a pair of spaced guards 23 is adjustably mounted on the bail bar 7, being held in adjusted position on the bar by means of screws 24, as more fully explained in the copending application of George F. Handley, Serial Number 170,451.

The ribbon supply means D includes a mounting bracket comprising a vertically disposed plate 25 supported on the carriage end plate 2 by means of arms 26-26, and a ribbon-carrying spool 27 journaled on a stud 28 fixed to the bracket plate 25. A nut 29 has threaded engagement with the stud 28 and is adapted adjustably to press the spool 27 against a frictional washer 30 for varying the resistance of the spool to rotation, and hence for varying the tension of the ribbon 22.

In the form shown, the spool 27 is mounted in a vertical plane so as to reduce the over-all length of the carriage, and, in order to position the ribbon 22 properly along the printing line of the platen, it must be twisted partially. To this end there is provided a twisting and guiding means comprising a roller 31 rotatable about a horizontal axis and a guide member 32 which is positioned in a vertical plane but which is inclined at an angle of substantially forty-five degrees to the horizontal. The ribbon 22 is led from the spool 27 underneath the roller 31 and thence over the guide member 32, and after leaving the guide member 32 the ribbon passes between fingers 33 which maintain the ribbon properly positioned along the printing line of the platen. The treated surface of the ribbon 22 is disposed upwardly as it passes under the guide member 31. Hence, in order to prevent rubbing of the transfer medium off the ribbon, the guide member 31 preferably is mounted for free rotation, and thereby any harmful rubbing of the treated surface of the ribbon is avoided.

The feeding means generally designated E is mounted at the end of the carriage opposite that at which the ribbon supply means is supported. Some of the parts of the feeding means are mounted on the lower side of the shelf 13 which, as before stated, is formed as an extension of the carriage end plate 1. In the Royal standard typewriting machine, a plate formed with a carriage return lever stop usually is positioned underneath a shelf corresponding to the shelf 13. Positioning of such a plate under the shelf 13 in the construction disclosed herein would interfere with the desired mounting of ribbon feeding parts. Accordingly a combined carriage return lever stop plate and spring tension mount or plate 34 is, in the present construction, supported on top of the shelf 13. This arrangement facilitates mounting of the ribbon feeding parts compactly under the shelf 13. A spring 35 is connected at one end to the line spacing lever as at 36, and is connected at its other end to a downwardly projecting part 37 of the plate 75

34. The spring 35 tends to move the line spacing lever 14 in a clockwise direction as viewed in Figures 1 and 2. A stop 38, which extends upwardly from the plate 34, is engageable by the line spacing lever 14 for limiting the movement thereof under the urge of the spring 35.

Cooperating with the shelf 13 for mounting the feeding mechanism is an extension bracket forming a lower shelf 39 secured to the carriage end plate 1 as at 40-40. A shaft 41 extends through an aperture 42 in the shelf 13 and through an aperture 43 in the lower shelf 39. The shaft is formed adjacent its upper end portion with an enlargement 44, and immediately above this enlargement with another and smaller enlargement 45 which abuts against the bottom face of the shelf 13. A spacing sleeve 46 having an eccentric portion 46a is mounted on the shaft 41 above the plate 13, and is adapted to be clamped against the plate by means of a nut 47 on the extreme upper end of the shaft 41. The sleeve 46 may be rotated about the shaft 41 to cause the eccentric portion 46a to cooperate as a stop with the line spacing lever 14 at selected different positions in order to adjust the extent of movement of the line spacing lever required for proper cooperation with the link 16, the rock arm 17, the pawl 18, and the ratchet 19. In order to effect an adjustment of the eccentric portion 46a, the nut 47 is loosened and the sleeve 46 is turned, after which the nut 47 is drawn up so as both to lock the eccentric 46a in adjusted position and at the same time to anchor the shaft 41 securely to the shelf 13.

A toothed or serrated feed roll 48 is mounted for rotation on the shaft 41 below the shaft enlargement 44 and meshes with a feed roll 49 which is journaled on a headed pintle 50 secured to an adjustable mount or plate 51 carried by the shelf 13 on the lower side thereof. The ribbon 22 is trained between and gripped by the rolls 48 and 49, and is fed by rotation of the rolls in a manner later to be described.

In order to facilitate placement of the ribbon between the rolls, the plate 51, and hence the pintle 50 and roller 49, are mounted for movements towards and away from the fixed axis roll 48. The plate 51 is mounted for both sliding and pivotal movements with respect to the axis of the gear 48. As shown, the plate 51 is formed with an elongated slot 52 which receives the enlargement 45 of the shaft 41. The enlargement 44 of the shaft, however, overlaps the slot 52 so as to maintain the inner end of the plate 51 against the lower side of the shelf 13. The front edge 53 of the shelf 13 is slotted as at 54 and receives for sliding movements the outer end portion of the plate 51, thereby maintaining the plate snugly against the bottom surface of the shelf 13. A spring 55 is connected at one end to a stud 56 on the plate 34, and is connected at its other end to a stud 57, the reduced lower end of which has threaded connection with the plate 51. An eccentric 58 is held in place by the stud 57 and is positioned to engage the adjacent face of the shelf 13 so as to limit movement of the plate 51 under the urge of the spring 55. The eccentric 58 may be turned to any desired position in order selectively to fix the spacing of the rolls 48 and 49 so as to grip the ribbon 22 with any desired pressure. A finger piece 59 is provided on the plate 51 for moving the plate outwardly against the urge of the spring 55 so as to separate the rolls 48 and 49, to facilitate placing the ribbon between them. In order to lock

the plate 51 in its retracted position, the plate is formed with a notch 60 adapted to cooperate with a notched edge 61 on an extension 62 of the carriage end-plate 1.

In operation, the feed roll 48 is rotated during line spacing movement of the platen and drives the idler feed roll 49 with which it meshes, the two cooperating to feed the ribbon 22 along the printing line of the platen. The means for effecting this rotary movement of the roll 48 constitutes an important feature of the invention.

The feed rolls 48 and 49 are arranged to be operated when the carriage return lever 14 is actuated to move the carriage to the right after the typing of a line has been completed. The carriage return lever 14 is formed with a rearwardly projecting arm or extension 63, the extreme rear end of which is T-shaped, and serves to mount a gear segment 64 which is secured as at 65 to the arm 63 of the carriage return lever, the pitch circle of the segment having its center coincident with the axis of rocking of the lever 14. The segment 64 is arranged to mesh with a small pinion 66 mounted on a pintle 67 supported by a bracket 68 secured to the shelf 13. A disc 69 is secured to the pinion 66 so as to rotate in unison therewith about the pintle 67. A driving pawl 70 is pivotally mounted on the disc 69 as at 71, and is arranged to engage the teeth of a ratchet 72 which is brazed to a large gear wheel 73 rotatable about the pintle 67. The arrangement is such that, when the pinion 66 and disc 69 are rotated in a counterclockwise direction as viewed in Figures 1 and 2, the gear 73 will be driven in the same direction through the medium of the pawl 70 and the ratchet wheel 72. The gear 73 is in constant mesh with the feed roll 48, so that the counterclockwise movement of the gear 73 will drive the feed rolls 48 and 49 in a direction to effect feeding of the ribbon or strip 22. In order to prevent rotation of the gear wheel 73 in the reverse direction, a check pawl 74 is pivotally mounted as at 75 on the shelf 39.

In operation, and assuming that the typing of a line has just been completed, the line spacing lever 14 will be actuated in the usual manner to effect line spacing movement of the platen 3 and also to return the carriage to its right hand position preparatory to typing a new line. This will result in rocking of the line spacing lever in a counterclockwise direction about the pivot 15, whereby the pinion 66 will be driven in a counterclockwise direction by the gear segment 64 so as to drive the feed rolls 48 and 49 through the medium of the disc 69, the pawl 70, the ratchet 72, and the gear wheel 73. The oscillatory segment 64 and other gears are so proportioned as to provide speed multiplying gearing between the line spacing lever and the feed roll 48, whereby operation of the line spacing lever effects a plurality of revolutions of the feed roll. The relative pitch diameters of the gear segment 64, the pinion 66, the gear wheel 73, and the feed roll 48 are such that this operation will result in the feeding of a relatively long strip of ribbon 22 corresponding substantially in length to the length of an average typed line so as to present a fresh portion of transfer medium ribbon along the line of typing before the start of each new line.

The typewriting machine disclosed herein embodies the invention in a preferred form, but it will be understood that various changes may be made in the construction and relative arrange-

ment of the parts without departing from the invention as defined in the claims.

I claim:

1. In a typewriting machine, a carriage; a platen journaled thereon for line spacing movements; a line spacing lever pivotally mounted on the carriage; a ribbon feed roll journaled on the carriage; a pinion having driving connection with said feed roll; and a gear segment mounted for oscillatory rotary movement together with said line spacing lever about the pivot of said line spacing lever and meshing with said pinion.
2. In a typewriting machine, a carriage; a platen journaled thereon for line spacing movements; a combined line spacing and carriage return lever pivotally mounted on the carriage; a ribbon feed roll journaled on the carriage; a pinion having driving connection with said feed roll; and a gear segment meshing with said pinion and being connected to the lever for conjoint rotary movement therewith about the pivot of said lever for imparting rotation to the feed roll during line spacing and carriage return movement of the lever, the diameter of the gear segment being relatively large as compared to the diameter of the pinion.
3. In a typewriting machine, a carriage; a carriage return lever pivotally mounted on the carriage and having a handle portion extending forwardly of the lever pivot; a ribbon feed roll mounted on the carriage; and speed multiplying gearing interposed between the feed roll and the carriage return lever for imparting a plurality of revolutions to the feed roll in response to pivotal movement of the lever when the latter is operated to effect return movement of the carriage, said gearing including a pinion mounted to rotate on an axis behind the carriage return lever pivot and having driving connection to said feed roll, a gear segment meshing with said pinion, and an arm secured to said carriage return lever and extending rearwardly of the pivot thereof for mounting said segment to move together with said lever behind the lever pivot.
4. In a typewriting machine, a carriage; a carriage return lever pivotally mounted on the carriage and having a handle portion extending forwardly of the lever pivot; a ribbon feed roll mounted on the carriage; and speed multiplying gearing interposed between the feed roll and the carriage return lever for imparting a plurality of revolutions to the feed roll in response to pivotal movement of the lever when the latter is operated to effect return movement of the carriage, said gearing including a pinion mounted to rotate on an axis behind the carriage return lever pivot and having driving connection to said feed roll, a gear segment meshing with the pinion, an arm secured to said carriage return lever and extending rearwardly of the pivot thereof for mounting said segment to move together with said lever behind the lever pivot, and a one-way drive connection between said pinion and said feed roll.
5. In a typewriting machine, a carriage; a carriage return lever pivotally mounted on the carriage to rock about a vertical axis and having a handle portion extending forwardly of the lever pivot; a ribbon feed roll mounted on the carriage to rotate about a vertical axis; a pinion mounted on the carriage to rotate about a vertical axis behind the lever axis; driving connections between the pinion and the feed roll; a carriage return lever extension fast with the carriage return lever and projecting rearwardly

of the lever axis to rock with the lever about its vertical axis; and a gear segment fast on the end of said extension remote from and behind said carriage return lever axis and meshing with said pinion, the pitch circle of said gear segment having its center coincident with the carriage return lever axis of rocking.

6. In a typewriting machine including a carriage and a platen journaled thereon for line-spacing movements, mechanism for feeding ribbon in such relation to typing operations as to position a fresh unused ribbon portion for typing impressions substantially at all times, said mechanism comprising a combined line-spacing and carriage return lever mounted on the carriage; a ribbon feed roll journaled on the car-

riage; means for training ribbon along the writing line of the platen and to said feed roll; and speed multiplying gearing interposed between and drivingly connecting the feed roll and the lever for imparting a plurality of revolutions to the feed roll in response to a single movement of the lever when the latter is operated to effect line-spacing movement of the platen and return movement of the carriage, the diameter of the feed roll, the length of the platen, and the ratio of said gearing being so related to each other that said operation of said lever will effect the feeding of a strip of ribbon corresponding substantially in length to the length of an average typed line.

JOHN JOSEPH KITTEL.
